UNITED STATES PATENT OFFICE.

JAMES WILLARD HALL, OF BRIGHTON, MASSACHUSETTS, ASSIGNOR TO THE MOORE PEN COMPANY, OF BOSTON, MASSACHUSETTS, A CORPORATION OF MASSACHUSETTS.

DESIGN FOR AN ELECTRIC-LIGHT GLOBE.

Application filed August 21, 1925. Serial No. 14,551. Term of patent 3½ years.

To all whom it may concern:

Be it known that I, JAMES WILLARD HALL, a citizen of the United States of America, residing at Brighton, in the county of Suffolk and State of Massachusetts, have invented a new, original, and ornamental Design for an Electric-Light Globe, of which the following is a specification, reference being had to the accompanying drawing, forming part thereof.

Fig. 1, is a top view of an electric light globe showing my new design.

Fig. 2, is a side view thereof.

I claim:

The ornamental design for an electric light globe, as shown.

In testimony whereof I affix my signature.

J. WILLARD HALL.
